UNITED STATES PATENT OFFICE.

THOMAS MITCHELL BLACKWELL, OF BASIC CITY, VIRGINIA.

RAILWAY-CROSSING GATE.

Application filed November 22, 1924. Serial No. 751,635.

To all whom it may concern:

Be it known that I, THOMAS MITCHELL BLACKWELL, a citizen of the United States, residing at Basic City, in the county of **5** Augusta and State of Virginia, have invented a new and useful Railway-Crossing Gate, of which the following is a specification.

This invention relates to railway crossing **10** gates and aims to provide novel means whereby the gates at a railway crossing may be automatically operated by a train moving in proximity thereto.

Another important object of the invention **15** is to provide means whereby the gates will be raised and lowered slowly eliminating any possibility of damage to the gate structure by allowing the gate to drop suddenly.

20 Another object of the invention is to provide means for returning the gates to their inactive positions, after a train has passed the crossing.

With the foregoing and other objects in **25** view which will appear as the description proceeds, the invention resides in the combination and arrangement of parts and in the details of construction hereinafter described and claimed, it being understood **30** that changes in the precise embodiment of the invention herein disclosed, may be made within the scope of what is claimed, without departing from the spirit of the invention.

35 Referring to the drawings:

Figure 1 is a plan view disclosing gates and operating means constructed in accordance with the invention.

Figure 2 is a side elevational view thereof.

40 Figure 3 is a sectional view taken on line 3—3 of Figure 2.

Figure 4 is an enlarged detail view of one of the operating members.

Figure 5 is an elevational view disclosing **45** the means for normally locking the gates in their open positions.

Figure 6 is a side elevational view of one of the gates and operating means.

Figure 7 is a perspective view of the gate **50** supporting shaft and latch controlling shaft.

Figure 8 is a sectional view through the bell employed as a signal at the gate for warning persons of an approaching train.

55 Referring to the drawings in detail, the reference character 5 indicates the rails of

a railway track and the reference character 6 indicates a roadway over which the rails cross.

The gate supporting shaft is indicated at **60** 7 and is mounted in bearing members 8 that are secured to one of the ties on which the rails of the track are positioned. The gates which are indicated at 9 have one of their respective ends secured to the shaft 7 to move with the shaft so that when the operating mechanism to be hereinafter more fully described is operated to move the shaft, the gates will be automatically moved **65** to their open or closed positions. **70**

Each gate embodies a relatively long arm 9 and a short arm 10 extending at right angles thereto, the short arm 10 being formed with openings 11 to accommodate the shaft 7 for securing the gates to the **75** shaft.

Pivottally mounted at the outer end of each gate 9 is an arm 12 formed with a foot 13 which is adapted to move downwardly with the gate and rest on the ground **80** surface to support the outer end of the gate.

A locking disk indicated at 14 is also mounted on the shaft 7 and as shown is formed with a notch disposed in its periphery to be engaged by the right angled end **85** of the latch member 15, which latch member is secured to the latch controlling rod 15' which is secured to one of the ties of the railway track by means of the bearing members 16. **90**

The locking disk 14 is eccentrically supported and is engaged by the friction member 6' which is spring pressed to set up a binding action on the disk 14 to prevent the gate from moving too suddenly to its closed position. Supported at one end of the rod **95** 15' is an arm 17, which is formed with an opening to receive one end of the cable 18 which has its opposite end connected to the lower end of the arm 19 of the gate releasing member at 20, the arm 19 being formed with an opening to accommodate the pin 21 whereby the gate releasing member may be pivotally supported adjacent to the gate. **100**

This gate releasing member also includes **105** a shoe engaging portion 22 and a downwardly curved portion 23, the downwardly curved portion 23 being formed with a stop 24 against which the coiled spring 25 abuts. The coiled spring 25 is positioned on the reduced end 25' of the curved portion 23 of the gate releasing member and is held in

the tubular supporting member 26 which is also arranged adjacent to the gate. From the foregoing it will be obvious that as the operating member moves downwardly, the 5 arm 19 will be moved to move the shaft 15' and latch member 15, supported at one end thereof. The operating member is adapted to be engaged by the arm 27 that is carried by the train, the arm being pivotally supported in such a way that upon reverse movement of the train carrying the arm, the arm will be swung rearwardly to pass freely over the operating member.

10 The gate operating mechanism includes a 15 supporting bar 28 provided with upwardly extended bearings 29 that support sprocket wheels 30 over which the chain 31 operates. Supported adjacent to the sprocket 30 and mounted to operate therewith is a relatively 20 small sprocket 32 that transmits motion to the sprocket 33 through the chain 34, the sprocket 33 being supported on a shaft mounted in a suitable opening formed in the arm 35.

25 The sprocket wheel 36 is also mounted adjacent to the sprocket 35 and transmits movement to the sprocket 37, through the chain 38. The sprocket 39 is mounted at one end of shaft 7 and receives motion from 30 the relatively small sprocket 40 through chain 41. Thus it will be seen that movement of the chain 31 is transmitted to the shaft 7 to move the gates supported thereon to their inactive positions, the reduction in 35 the gearing being such as to cause the shaft to move slowly to the end that the gates will be gradually lifted.

Supported by the chain 31 and extending upwardly therefrom is an arm 42 that 40 lies in the path of travel of the arm 27 carried by the train to the end that the arm 42 will be engaged by the arm 27 and carried forwardly to operate the chain 31.

45 The gate operating mechanism as described is designed for moving the gates to their inactive position when a train passing over the tracks, and moving in one direction, has passed the road crossing.

50 It is to be understood that at the opposite side of the track, a gate operating mechanism identical with that described is employed for moving the gates to their open or inactive positions, by a train moving in the opposite direction, with the exception 55 of the provision of a pulley 43 which is carried by the sprocket 37 of this operating mechanism. Movement of the pulley 43 is transmitted to the shaft 7, by means of the pulley 44 and flexible member 45.

60 The gate releasing member at this side of the road crossing is identical with that described, and it is believed that further detail description of this structure is unnecessary, however it might be added that a 65 cable 46 has connection with the arm 19 of

this releasing member, the forward end of the cable 46 being connected with the vertical arm 47 that has its upper end connected with the vertical arm 48 by the rod 49. The lower end of the arm 48 having connection with the cable 50 which extends to a point in proximity to the shaft 7 where it connects with the lower end of the arm 51 which is secured to the rod 15' so that movement of the arm 51 will produce a relative movement 70 of the rod 15'. As an operating arm of a train moves over the shoe at this side of the road crossing, it will be obvious that the latch member will be operated to release the gates and allow them to swing 75 downwardly, under their own weights.

80 A flexible member indicated at 52 is secured to one of the gates as clearly shown by Figure 2 of the drawings, the intermediate portion thereof passing over the roller 53. A weight 54 is carried at the free end of the flexible member 52 to cause the flexible member 52 to be returned to its normal 85 position as the gates move upwardly.

90 This flexible member 52 also acts to operate the tappers 54' which are mounted on one end of the shaft 55 that carries the roller 53, the tappers 54' being shown as operating within the bell 56, so that as the shaft 55 is rotated, the bell will be sounded 95 to signal to persons approaching the railway crossing that the gates are being lowered, and a train is nearing the crossing.

100 Adjustable weights 60 are mounted on the gates 9 and are adapted to overbalance the gates to cause them to move when the latch mechanism has been released.

105 In order that the gates may be seen at night, when they are lowered, a lantern indicated at 57 is carried by each gate and supported in such a way that when the gates are in their open positions, they will swing behind the members 58 but that when the gates are in their closed positions, the lanterns will swing down to a position to be 110 clearly visible.

115 In the operation of the device, assuming that a train is moving in the direction of the arrows as indicated by Figure 2 of the drawings, it will be obvious that the arm 27 will move into engagement with the latch releasing member, to the end that the same will be depressed, moving the shaft 15' in a manner to elevate the latch member out of engagement with the disk 14, whereupon the gates may swing downwardly under their 120 weights.

125 As the train passes the road crossing, the arm 27 will engage the arm 42 carried by the chain at one side of the road crossing, to the end that the chain 31 will be operated to move the shaft 7 and gates supported thereby, causing the gates to take an open position.

130 It will be seen that on the movement of

a train in a direction opposite to the direction indicated by the arrows, the latch operating mechanism at the opposite side of the track, and the gate operating mechanism 5 at the opposite side of the track will be operated to accomplish the result as described.

While I have shown and described a gate employed on a single track, it is to be understood that with slight changes, the device 10 may be efficiently employed in operating gates adjacent to crossings, or double tracks without departing from the spirit of the invention.

I claim:—

15 1. A gate operating mechanism including a gate supporting shaft, a disk eccentrically mounted on the shaft and having a notch portion, a latch member disposed within the notched portion for holding the shaft normally against movement, train controlled means for operating the latch member to release the shaft to permit the gates supported thereby to move to their active positions, and gate controlled means for returning the 20 shaft and gates to their normal positions.

25 2. A gate operating mechanism including a gate supporting shaft, a disk eccentrically mounted on the shaft and having a notch portion, a latch member adapted to engage 30 within the notched portion to hold the shaft against movement, the friction member

adapted to engage the disk to retard movement of the shaft and gate supported thereby, and train controlled means for operating the 35 shaft to return the shaft and gates to their inactive positions.

3. A gate operating mechanism including a gate supporting shaft, a latch member, means carried by the shaft and engaged by 40 the latch member to normally prevent rotation of the shaft, train controlled means for releasing the latch member, and means for retarding movement of the shaft.

4. A gate operating mechanism including 45 a gate supporting shaft, gates on the shaft, a disk on the shaft, a latch member cooperating with the disk to normally prevent movement of the shaft, a latch operating member supported adjacent to a railway rail and 50 adapted to be engaged by a depending arm carried by the train passing thereover, to move the latch operating member, and means for connecting the latch and latch operating member to release the gates and permit them 55 to move to their closed positions.

In testimony that I claim the foregoing as my own, I have hereto affixed my signature in the presence of two witnesses.

THOMAS MITCHELL BLACKWELL.
